UNITED STATES PATENT OFFICE.

STEPHEN A. DOBYNE, OF ST. LOUIS, MISSOURI, ASSIGNOR TO CHAMPION SHOE MACHINERY COMPANY, OF ST. LOUIS, MISSOURI, A CORPORATION OF MISSOURI.

THROAT FOR FASTENER-INSERTING MACHINES.

1,091,300.

Specification of Letters Patent. Patented Mar. 24, 1914.

Original application filed March 18, 1912, Serial No. 684,653. Divided and this application filed June 18, 1913. Serial No. 774,379.

To all whom it may concern:

Be it known that I, STEPHEN A. DOBYNE, a citizen of the United States, and residing at St. Louis, in the State of Missouri, have 5 invented certain new and useful Improvements in Throats for Fastener-Inserting Machines, of which the following is a specification.

This invention relates to throats for fastener inserting machines and this application is a division of application Serial No. 684,653, filed March 18, 1912.

One of the objects of this invention is to provide means for guiding the fastener 15 while passing through the throat and while being driven so as to support the same against lateral movement while being driven into the material.

Further objects will appear from the detailed description taken in connection with the accompanying drawing in which:

Figure 1 is a detail front elevation of a fastener inserting machine, showing the novel throat, Fig. 2 is a detail section on the line 2—2 Fig. 1, Fig. 3 is a section on the line 3—3 Fig. 2, Fig. 4 is a detail perspective view of the die, and Figs. 5, 6, 7 and 8 are diagrammatical views illustrating the mechanism for guiding the fastener while being driven.

Referring to the accompanying drawing, 15 designates a machine head, 16 a driver, 21 a throat, 23 a fastener stock guide, 25 a cutter, and 28 an awl, the parts being arranged 35 as shown in the application referred to.

The throat is provided with a removable die 36 having a positioning dowel 37 and clamped to the throat by means of a screw 38. This die is bowed upwardly at its center 40 with respect to the throat as shown in Fig. 4 so that when clamped in position, the cutting end will be clamped firmly against the throat. The cutting edge is beveled and undercut as shown in Fig. 3.

45 The throat is channeled as shown in Figs. 1 and 2 and has mounted thereon a guide member 39 which is pivoted at its upper end by means of a screw 40 passing through an elongated slot in the guide member. This guide member has a fin projecting into the driver passage, and this fin is formed as shown in Figs. 3 to 8 inclusive, with an upper inclined portion 41, an intermediate substantially vertical portion 42, and a lower in-

clined portion 43, forming together a series 55 of steps. A plunger 44 mounted in a tubular bore 45 bears against the member 39 and is pressed thereagainst by means of a spring 46 on the shank 47. The throat body is provided with a shoulder 48 forming an abutment 60 for the head of the plunger 44, and this plunger and its tubular casing are bolted to the throat by means of a screw 49. The guide member can be readily removed by removing the screw 40 when the guide 65 member can be pushed downwardly out of its channel. The shoulder 48 limits the movement of the plunger when the guide member is removed. The fin and the spring 70 plunger, the spring of which is comparatively strong, operate to retain the guide member in position in the throat even when the pivot pin 40 is removed.

The guide is arranged to move toward and from the opposite throat wall at both ends, 75 since the lower end is free and the upper end has a loose connection with its pivot 40, and since the plunger 44 bears against this member at a point intermediate its pivotal connection and its free end. The construction 80 of the fin is such that it will constantly and at all times bear against two separated points of the head side of the string nail during practically the entire passage of this nail through the driver passage, and this 85 engagement is at the head and a point on the shank of the nail. The nail will thus be held firmly with its flat and straight side against the straight vertical wall of the driver passage. This engagement of the 90 guide member with the nail at a plurality of separated points along its length is continued until the nail projects a considerable distance beyond the throat, as shown in Fig. 8, and until the nail has entered the material 95 for a considerable distance. While the nail is projected through the throat and into the material, the nail is thus firmly supported at both the head and the shank, as shown in Figs. 7 and 8, so that the nail cannot move laterally at this time. The nail is thus supported against transverse movement during its entire passage through the throat and until it is practically driven. This results in a uniform drive and prevents 100 the nail from turning, bending or curling while passing into and through the material.

It is obvious that various changes may

be made in the details of construction without departing from this invention, and it is therefore to be understood that this invention is not to be limited to the specific construction shown and described.

Having thus described the invention what is claimed is:

1. In a fastener inserting machine, a throat having a driver passage, and means in 10 said driver passage constructed and arranged to yieldingly engage and support a fastener against transverse movement at a plurality of separated points along its length during substantially its entire passage through said driver passage as it is being driven therethrough.
2. In a fastener inserting machine, a throat having a driver passage provided with a straight wall constructed to guide the 20 straight side of a headed fastener, and means in said driver passage constructed and arranged to yieldingly engage the head side of the fastener at a plurality of separated points along its length and yieldingly hold it 25 against said wall and against transverse movement during substantially its entire passage through said driver passage as it is being driven therethrough.
3. In a fastener inserting machine, a throat having a driver passage provided with a straight wall constructed to guide the straight side of a headed fastener, and means in said driver passage constructed and arranged to yieldingly engage both the 30 head and shank of the fastener during substantially the entire passage through said driver passage as it is being driven therethrough.
4. In a fastener inserting machine, a throat having a driver passage, a member in 40 said driver passage constructed and arranged to yieldingly engage and guide a fastener, and means for supporting said member constructed to permit both of its ends to move 45 independently toward and from the opposite wall of the driver passage, said member being constructed and arranged to yieldingly engage and support a fastener against transverse movement at a plurality of separated 50 points along its length during substantially its entire passage through said driver passage as it is being driven therethrough.
5. In a fastener inserting machine, a throat having a driver passage for a headed 55 fastener, a member in said driver passage constructed and arranged to yieldingly en-

gage the head and shank of the fastener, and means for supporting said member constructed to permit said member to automatically adjust itself to the fastener as it passes 60 through said driver passage to constantly maintain its engagement with both the head and shank of the fastener during substantially its entire passage through said driver passage.

6. In a fastener inserting machine, a throat having a driver passage, a member in 65 said driver passage, and means for pivotally supporting said member at one end constructed to permit movement of said member 70 at its pivot toward and from the opposite driver passage wall, and a spring bearing against said member between its ends, said member being constructed and arranged to yieldingly engage and support a fastener 75 against transverse movement at a plurality of separated points along its length during substantially its entire passage through said driver passage as it is being driven therethrough.

7. In a machine of the class described, a throat having a driver passage, a fastener guiding member removably mounted in said 80 throat, a spring pressed plunger bearing against said guiding member, and a stop for limiting the movement of said plunger when 85 said guiding member is removed.

8. In a machine of the class described, a throat having a driver passage, and a recess adjacent said driver passage, a fastener 90 guiding member removably mounted in said recess and having a fin projecting into said driver passage, a spring pressed plunger bearing against said guiding member, and a stop for limiting the movement of said plunger 95 when said guiding member is removed.

9. In a machine of the class described, a throat having a driver passage and a recess adjacent said driver passage, a fastener guiding member mounted in said recess and 100 having a fin projecting into said driver passage, and a spring bearing against said guiding member, said guiding member being retained frictionally in position in said throat by said fin and spring and being endwise removable therefrom.

In testimony whereof I affix my signature in the presence of these two witnesses.

STEPHEN A. DOBYNE.
